UNITED STATES PATENT OFFICE.

HENRY A. WAGNER, OF TOLEDO, OHIO, ASSIGNOR TO THE WILLYS-OVERLAND COMPANY, OF TOLEDO, OHIO, A CORPORATION OF OHIO.

CLIP-BENDING MACHINE.

Application filed September 1, 1922. Serial No. 585,645.

This invention relates to machines for bending wire clips such for example as are employed to connect adjacent springs of spring cushions and it is an object of this invention to provide an improved machine of this nature which shall automatically convert a continuous length of wire into clips of the desired shape.

Other objects relating to details of construction and economies of manufacture will appear as I proceed with the detailed description to follow.

A structure constituting an embodiment of my invention is illustrated in the accompanying drawing forming a part of this specification in which:

Figure I is a top plan view of the complete machine.

Fig. II is a front elevation of the same.

Fig. III is a vertical sectional view through the main shaft taken on the line III-III of Fig. I.

Fig. IV is a vertical sectional view taken on the line IV-IV of Fig. I.

Fig. V is a fragmentary sectional view corresponding to Fig. IV taken on the line V-V of Fig. I.

Figs. VI, VII and VIII are vertical sectional views taken respectively on lines VI, VII and VIII of Figure I.

Fig. IX is a fragmentary view, on a larger scale of the cut-off mechanism.

Figs. X to XIII inclusive are diagrammatic views showing the various stages of bending the wire clip and

Fig. XIV is a perspective view of a finished wire clip.

Throughout the drawing the same reference numbers refer to the same parts of the structure.

A base frame 5 supports a main shaft 6 having a tight pulley 7 and a loose pulley 8 and also a shaft 9 connected by spur gearing to be intermittently rotated from the main shaft 6 by a Geneva movement 10. By this means the shaft 9 is given one rotation each time the main shaft completes a rotation and its movement serves to reciprocate a cross head 11 sliding on a guide 12, connection being made through a connecting rod 13 and disk 14 mounted on the shaft 9. The wire from which the clips are made passes from a reel or coil not shown, through the straightening rolls 15 to a gripping device 16 on the cross-head 11 from whence

it passes through a second gripping device 17 and through a guide 18 to the bending mechanism. The parts thus far described are well known in wire bending machines and form no part of my invention.

Before proceeding with the description of that part of the machine by which the wire is bent into the desired form, I shall describe briefly the various bending operations by means of the diagrammatic views comprising Figs. X to XIII. The wire, indicated by the letter W, after passing

through the oscillatable guide 18 and over the shear member 20 by which it is cut into the proper lengths extends across the face of each of three rotatable heads 21, 22 and 23. Each head has a forwardly extending lip or segment 24 and a central rod 25, the wire passing between the segment and the rod in each case. Starting with the parts

in the position shown in Fig. X the first operation after the wire is cut off, is the rotation of the two outer heads, 21 and 23 to the positions shown in Fig. XI, thus forming a hook at each end of the wire.

The head 21 is then rotated in the opposite direction to its original position and the central rod 25 is withdrawn to free the hook thus formed. By the next operation, the center head 22 is rotated to the position indicated by Fig. XIII thus bending the wire double intermediate its ends. The center head is now returned to its original position and the center rods of both heads 22 and 23 are withdrawn as in the case of head

21. The clip thus formed drops into a receptacle and due to the resilience of the wire of which it is made takes the form substantially as illustrated by Fig. XIV. After the head 23 has returned to its original position the parts are in position to receive another length of wire upon which the above described operations are repeated.

The mechanism by which the above described operations are effected will now be described. As before stated, the cutting off of the wire is done by the rocking movement of the guide 18 adjacent the shear member 20. This guide is pivotally mounted and has an arm 30 carrying a roller 31 held by a coil spring in engagement with a cam 32 on the main shaft 6. A length of wire is thereby cut off at each rotation of the main shaft. Each of the three heads 21, 22 and 23 comprises the outer end of a

110

100

105

105

spindle such as is illustrated by 33 in Fig. IV in connection with the head 23. This spindle has a suitable bearing in the block 34 and is retained by a strip 35. Guideways 36 are formed in the upper portion of the frame in which slide racks 37, 38 and 39 which engage pinions 40, 41 and 42 formed respectively upon the spindles having heads 21, 22 and 23. The opposite end of each rack carries a roller which rollers bear respectively against cams 43, 44 and 45 carried by the main shaft 6. Rack 39 has an enlargement provided with an elongated opening to receive the main shaft, the roller on the end of this rack being positioned to engage the cam 45 to the right of the shaft instead of on the left as in the case of the two other racks. Suitable springs 47 engaging pins 48 in the racks serve to hold the rollers against the cam faces. By this mechanism the heads 21, 22 and 23 are caused to rotate the desired amounts and at the proper times.

In order to effect the release of the wire clip after it has been bent to the desired shape the central rods 25 must be withdrawn. These rods are in reality the reduced ends of larger rods 50 which extend through the spindles 33.

A slide 51 having a roller 52 operated by a cam 53 on shaft 54 connects as shown with the rear ends of two of the rods 50, namely the rods belonging to heads 22 and 23 so that at each rotation of the shaft 54 the central rods 25 of heads 22 and 23 are drawn back and then released. Return movement of the slide 51 and rods connected therewith is effected by a coil spring 55 and the shaft 54 is rotatably connected to the main shaft by a pair of miter gears 56. In order to be able to vary the length of the wire clip provision is made in the nature of spacing members or shims 57 between the members 34. It will be obvious that by changing these shims for thicker or thinner ones clips having any desired length may be formed. The entire assembly of bearing blocks 34 and shims is clamped rigidly in the frame by clamping bolts 58.

While the central rods 25 of the two heads 22 and 23 are operated simultaneously by the same cam and slide mechanism, the central rod of head 21 is operated by a separate slide 59, see Figs. I and V, carrying a roller 60 engaging a cam 61 on the same shaft 54. The cams 53 and 61 are so related to the cams on the main shaft that the wire clip is released at the proper time and the central rods pushed out in readiness for a new length of wire.

While I have shown and described in detail a particular preferred structural embodiment as illustrative of my invention, I do not wish to be limited thereby, since various changes might be made therein without departing from the spirit and scope of

the invention covered by the appended claims.

What I claim as new and desire to secure by Letters Patent is:

1. In a wire clip bending machine having means for intermittently feeding wire thereto, an oscillatable guide for said wire, a shear member adapted to cooperate with said guide to cut said wire into predetermined lengths, a main shaft, a cam thereon for oscillating said guide, a plurality of rotatable spindles having heads adapted to engage and bend said lengths of wire, cams on said shaft for operating said heads, an auxiliary shaft driven by said main shaft, cams thereon and rods within said spindles normally projecting beyond said heads, said rods being axially movable within said spindles and adapted to be drawn therebetween by said second named cams for releasing the bent lengths of wire from said heads. 75

2. In a wire clip bending machine, feeding and severing mechanisms for the wire, automatic means adapted to simultaneously bend the end portions of the wire into parallel relation with the middle portion thereof, and automatic means for subsequently bending the wire so that said end portions will lie opposite each other and in parallel relation. 80

3. In a wire clip bending machine, feeding and severing mechanisms for the wire, automatic means adapted at one operation to simultaneously bend the end portions of the wire so that they will lie parallel to the intermediate portion thereof when released by the bending means, and automatic means for subsequently bending the wire at its middle to bring said ends opposite each other. 100

4. In a wire clip bending machine for bending wires of a predetermined length, automatic means adapted to simultaneously bend the end portions of the wire so that they will be parallel to the intermediate portion thereof when released from said bending means, and automatic means for subsequently bending said intermediate portion so that said end portions will lie opposite each other and in parallel relation. 105

5. In a wire clip bending machine for bending wires of a predetermined length, automatic means adapted to first bend the end portions of the wire into parallel relation with the intermediate portion thereof, and then acting to bend said intermediate portion so that said end portions will register one with the other. 115

6. In a wire clip bending machine for bending wires of a predetermined length, three rotatable bending devices, two of which are adapted to bend the ends of the wire and the third adapted to bend the middle portion thereof, an operating shaft, and cams upon said shaft operatively connected with each of said rotatable devices, two of 125

said cams being adapted to simultaneously operate the devices for bending the ends of the wire and the other subsequently operating said third bending device.

5 7. In a wire clip bending machine for bending wires of a predetermined length, three rotatable bending devices, two of which are adapted to bend the ends of the wire and the third adapted to bend the middle portion thereof, an operating shaft, cams upon said shaft operatively connected with each of said rotatable devices, two of said cams being adapted to simultaneously operate the devices for bending the ends of the 10 wire and the other subsequently operating said third bending device, a second shaft connected with the first, and means operated thereby for causing one of said bending devices to release the portion of the wire bent 15 thereby and subsequently causing the remaining bending devices to move to release position.

8. In a wire clip bending machine for bending wires of a predetermined length, three 20 rotatable bending devices, two of which are adapted to first bend the ends of the wire and the third being adapted to subsequently bend the middle portion thereof, means for causing each of said devices to release the 25 wire at predetermined times, a shaft opera-

tively connected with said bending devices to effect rotation of each, and another shaft operatively connected with said devices to cause each to release the wire at predetermined times.

9. In a wire clip bending machine for bending wires of a predetermined length, three rotatable bending devices, two of which are adapted to first bend the ends of the wire and the third being adapted to subsequently bend the middle portion thereof, each of said devices including a releasable wire engaging member, automatic actuating means for said wire bending devices including a common operating member therefor, 40 and separate means for actuating said releasable members including a common operating member therefor.

10. In a wire clip bending machine for bending wires of a predetermined length, three rotatable bending devices, two of which are adapted to first bend the ends of the wire and the third being adapted to subsequently bend the middle portion thereof, a shaft, cams upon said shaft operatively connected with said bending devices for rotating each at the desired time, and means for actuating said shaft.

In testimony whereof I affix my signature.
HENRY A. WAGNER.
